UNITED STATES PATENT OFFICE.

CHARLES E. SQUIRES AND BENJAMIN F. SILLIMAN, OF CLEVELAND,
OHIO.

STEAM-TRAP.

No. 819,321.

Specification of Letters Patent.

Patented May 1, 1906.

Application filed February 24, 1905. Serial No. 247,071.

To all whom it may concern:

Be it known that we, CHARLES E. SQUIRES and BENJAMIN F. SILLIMAN, citizens of the United States of America, and residents of 5 Cleveland, county of Cuyahoga, and State of Ohio, have invented certain new and useful Improvements in Steam-Traps, of which the following is a specification.

Our invention relates to improvements in 10 contrivances provided to automatically expel condensation from steam-pipe lines or steam-pipe systems.

The object of our invention is to render such contrivance equally as well adapted for 15 high and low pressure service. We attain this object in an apparatus constructed and equipped as shown in the accompanying drawing, which represents a vertical sectional view of said apparatus.

20 Like letters of reference denote like parts in the drawing and specification.

The chief feature of this invention consists in the valve-releasing mechanism, which enables a ready discharge of the condensation 25 in the trap regardless of the prevalent steam-pressure within such traps. In the main this steam-trap comprises the vessel part A with lid B, the bucket C, the valves D and E, and a suitable bonnet, cage, and cover, reference 30 to which is had hereinafter.

The vessel part A has its steam-inlet at a, and opposite therefrom is located the lid B, which in any suitable manner may be held in secure connection with said vessel.

35 A drain for the sediment is shown at b.

About centrally near the bottom of the vessel is pivotally suspended the bucket C, as at c. The bucket C consists of a thin metallic structure and carries in hinged connection 40 the stem d for the valve D. The latter is thereby raised and lowered, according to position and condition of said bucket—that is, when or as long as said bucket is in buoyant condition the valve E is held closed against 45 the opening e by and through the intervention of valve D and stem d.

Normally the bucket C is held in buoyant condition or practically horizontal position until the water (condensation) in the vessel 50 attempts to rise above the top edge of the bucket, whereupon water will enter the bucket and fill it, in consequence whereof the bucket will tilt and pull the valve D from its seat. Following this the valve E recedes

from opening e to admit of a free discharge of 55 the water within the bucket, the water being forced out by the steam-pressure which is prevalent within the vessel above the water-line, and upon discharge of sufficient water the bucket will again become buoyant and 60 raise the valves D and E to hold the discharge-openings closed as long as the water-line in the vessel is below the edge of the bucket.

As shown, the bonnet F is secured to the 65 top of the vessel, and the tube f depends therefrom well nigh to the bottom of the bucket.

On top of the tube or face of the bonnet F is secured the cage H and cover I in any suitable manner, there being a space left between said cage and cover and a chamber h being formed in the bonnet in order to establish open relation with outlet g, wherefrom the water is conveyed to the sewer or some other 75 place, tank, or the like.

It is preferred to make the cage a separate part from the bonnet simply for convenience of construction and ease of accessibility. Within the cage is formed a suitable guide h 80 for both the valves D and E. Same is centrally suspended from the inner wall of cage H, leaving open relation from the entrance i to its outlet e'.

When the valve D is forcing the valve E 85 toward its seat e at the entrance of opening e', then pressure will immediately exert itself on the under side of said valve and hold same tightly against its seat, and were it not for the opening j in said valve the latter would 90 not recede, even though the stem d would be withdrawn by the sinking of the bucket. By way of the opening j, though, the pressure under valve E becomes released, and the latter will at once afford free exit for the water 95 through the outlet e', from where it reaches the discharge branch g, as above stated.

From the foregoing it can readily be seen that by providing a relief-valve in connection with the main valve any desirable discharge-opening can be used in such traps. A very rapid discharge can thus be obtained regardless to size of bucket and pressure of steam carried within such traps. Furthermore, the vital moving parts of this trap are so arranged 105 as to be of easy access without disconnecting any parts save the cover and cage.

With a minimum of attention and cost for

repairs a trap of this construction can be in service for an indefinite period, and fluctuations in steam-pressure will not and cannot affect its continuous automatic operation.

5 What we claim, and desire to secure by Letters Patent, is—

In a steam-trap the combination with the hinged bucket inside said trap and a removable bonnet located outside said trap and having a tube depending into said bucket, of a rod terminating in valve form, said rod being hinged to said bucket and extending upward through said tube, a valve-cage with top out-

let secured on top of said bonnet, an apertured cone-valve seating against the top outlet, guided in said cage and furnishing a seat for said rod-valve as shown and for the purpose set forth.

In witness whereof we have hereunto set out hands this 18th day of February, A. D. 20 1905.

CHARLES E. SQUIRES.
BENJAMIN F. SILLIMAN.
